UNITED STATES PATENT OFFICE.

JAMES BURBRIDGE, ROBERT C. THORPE, AND THOMAS OAKLEY, OF TOTENHAM, COUNTY OF MIDDLESEX, ENGLAND.

SYRINGE.

SPECIFICATION forming part of Letters Patent No. 240,086, dated April 12, 1881.

Application filed December 30, 1880. (No model.) Patented in England May 5, 1880, and in France September 16, 1880.

To all whom it may concern:

Be it known that we, JAMES BURBRIDGE, ROBERT CURETON THORPE, and THOMAS OAKLEY, all of Tottenham, in the county of Middlesex, England, have invented a certain new and useful Improvement in the Manufacture of Syringes, of which the following is a specification.

The object of our invention is to dispense with the use of valves of metal or similar material in the manufacture of enemas or syringes, and to so form the valves as to materially reduce the cost of manufacture and prevent any injury to the patient through the valves or parts thereof being corroded or otherwise acted upon by the liquid employed for injection.

To these ends our invention consists in a novel manner of forming the valve or valves of enemas or syringes in the india-rubber tubes thereof, whereby a simple and superior article is produced which is not liable to get out of order.

In the accompanying drawings, Figure 1 represents a side view, partly in section, of an enema or syringe embodying our invention. Fig. 2 represents a section of the end of the suction-tube and the suction-valve at right angles to Fig. 1. Fig. 3 represents a side view of the discharge-valve, taken at right angles to Fig. 1. Fig. 4 represents a side view of part of the syringe or enema; and Fig. 5 represents a core or device used in the manufacture, as hereinafter explained.

Similar letters of reference designate corresponding parts in the several figures.

In the drawings, *a* designates the ball, reservoir, or pump of the enema or syringe; *b* designates the suction-tube, and *d* the discharge-tube, all of which parts are formed of india-rubber by the processes commonly used in the manufacture of such articles.

The ball, reservoir, or pump *a*, which may be of any size or shape before it is vulcanized, has socket-pieces *c*, of hard-rubber compound inserted in its ends. A screw-threaded plug, *d'*, (see Fig. 4,) is then screwed into each socket-piece and the parts vulcanized.

The inner ends of the tubes *b* and *a* are provided with fittings, *e*, which, when the screw-plugs *d'* are removed, are screwed into the socket-pieces *c*. The nozzle *f* is also formed of hard-rubber compound, and is inserted into

the outer end of the delivery-tube previous to vulcanization.

So far as described our syringe or enema is not of novel construction, but its novelty consists in the manner of forming the valves.

The suction-valve *b'* is formed by turning in the end of the suction-tube *b*, as seen in Figs. 1 and 2, thus forming a collapsible portion, and inserting therein a flat wedge-shaped piece or core, *b*³, (shown in Figure 5,) to give said portion a flattened form. The insertion of the core *b*³ tends to elongate the turned-in end of the suction-tube, and thus reduces the thickness of the rubber at that part. The valve will thus take somewhat the shape of what is known to anatomists as a "mitral valve." The end of the tube *b*, wherein is the suction-valve *b'*, is enlarged, as shown in Fig. 1, to provide lateral space for the working of the valve.

The delivery-valve *c'* is formed by simply compressing or flattening the delivery-tube *d* while in the plastic state and before vulcanizing it, so that while it will open to permit the passage of liquid outward it will collapse and prevent air from being drawn into the ball or pump *a* during its expansion.

It will be understood that all the fittings are added to the tubes, and both valves are formed therein while the material is in a plastic state and before the tubes are vulcanized, and hence the valves by vulcanizing are given a permanent set.

The ball or pump *a* and the suction and delivery tubes may be formed in one continuous piece, and not of separate pieces, as here shown; but the valves are always to be formed in the manner described.

What we claim as our invention, and desire to secure by Letters Patent, is—

A syringe having flexible tubes, and having its valve or valves composed of flattened and collapsible portions of the sides of said tubes, substantially as specified.

Dated the 30th day of November, 1880.

JAS. BURBRIDGE.
ROBERT C. THORPE.
THOMAS OAKLEY.
